UNITED STATES PATENT OFFICE.

CLARENCE R. SNOW AND DANIEL J. FLOOD, OF QUINCY, MASSACHUSETTS.

MAGAZINE AND BOOK HOLDER.

Application filed January 31, 1928. Serial No. 250,816.

Our invention relates to magazine and book holders, designed for convenience in reading. The all inclusive generical term book is hereinafter used for convenience, and is intended to include magazines or other form of reading material.

Our invention has for its objects to provide an improved and inexpensive means for conveniently supporting and holding a book in open position for reading, rendering it easy to manipulate and handle; to provide a new and novel means for securing a book in such holding device; to provide a new and novel handle by which the device is readily grasped; to provide a new and novel means for preventing the page supporting wings of the device from opening beyond a position more or less opposite each other; to provide an improved anchorage for the hinges of the page supporting wings; to provide an improved channel adaptable to confine the bound edge of a book in its intended position; and to provide the various other advantages and results made evident from the following specification. Our device is preferably made from strong metal wire, but any suitable material may be used.

We accomplish the objects of our invention as shown in the accompanying drawing, which forms a part of this specification, and in which Figure 1 shows a plan view of our device in open position. Figure 2 shows an end view of the device with a book in open position therein. Figure 3 is a detail view corresponding to Fig. 1 inverted showing one of the holding plates. Figure 4 shows the ringed end of the center frame.

Referring again to the drawings, A shows the center frame preferably formed from one piece of material so as to render its sides parallel, joined and shaped at one end B to form an eye B² adaptable to receive one end C² of the center rod C, the opposite end C³ of which is twisted about the top of the frame A² to act as a hinge, on which hinge the center rod swings. The parallel parts of the frame A are secured and held in place by the plates D, preferably of metal, having extension fingers E and F which pass under, over and about the parallel parts of the frame A so as to firmly clinch the same, and forming with the body of the plate an anchorage within which the hinges on the page-supporting wings G operate.

The plates D are shouldered at D², the shoulders being positioned to engage, in

open position, the ends of the page-supporting wing wire G³ which ends G³ first encircle one of the parallel members of the center frame A. When the wings G are in open position, the shoulders in conjunction with the ends G³ function as a stop to prevent the page-supporting wings from opening beyond a position more or less opposite each other.

The outer edges G² of the wings G are bent inwardly at their center portions to form the handles or loops H, adaptable for use in grasping and holding the device while reading and otherwise.

Similar letters of reference refer to similar parts throughout the various views.

While we have illustrated and described a preferred construction for carrying our invention into effect, this is capable of variation or modification without departing from the spirit of the invention. We therefore do not wish to be limited to the exact details of construction herein set forth but desire to avail ourselves of such variations and modifications as come within the scope of the appended claims.

Having thus described our invention we claim as new and desire to secure by Letters Patent of the United States of America:

1. In a book holder a center frame formed with parallel side members, plates spanning said side members, gripping fingers on same which pass under, over and about said side members, so as to firmly clinch the same, said frame being adapted to receive the bound portion of a book; a holding rod hinged at one end to said center frame adapted to pass between the pages of a book; said center frame having at its opposite end a receiving eye adaptable to receive and hold the end of the holding rod opposite its hinged end; oppositely extending page-supporting wings hinged on the respective side members of said center frame so mounted that when disposed in open position the ends of the material from which said wings are formed register and engage with shoulders on said plates and function as stops, preventing said page supporting wings from swinging beyond their open position.

2. In a book holder a center frame formed with parallel side members, plates spanning said side members, gripping fingers on same which pass under, over and about said side members, so as to firmly clinch the same, said frame being adapted to receive the bound

- portion of a book; a holding rod hinged at one end to said center frame adapted to pass between the pages of a book; said center frame having at its opposite end a receiving eye adaptable to receive and hold the end of the holding rod opposite its hinged end; oppositely extending page-supporting wings hinged on the respective side members of said center frame so mounted that when disposed in open position the ends of the material from which said wings are formed register and engage with shoulders on said plates and function as stops, preventing said page-supporting wings from swinging beyond their open position; a handle positioned intermediate the edges of said respective page-supporting members, adapted for use in grasping and holding the device while reading and otherwise.
- 5 3. In a book holder a center frame formed with parallel side members, plates spanning said side members gripping fingers on same which pass under, over and about said side members, so as to firmly clinch the same, said frame being adapted to receive the bound portion of a book; said center frame having means for securing a book therein and oppositely extending page-supporting wings hinged on the respective side members 10 of said center frame so mounted that when disposed in open position the ends of the material from which said wings are formed register and engage with shoulders on said plates and function as stops, preventing said page supporting wings from swinging beyond their open position.
- 15 4. In a book holder a center frame formed with parallel side members, plates spanning said side members, gripping fingers on same
- which pass under, over and about said side members, so as to firmly clinch the same, said frame being adapted to receive the bound portion of a book; said center frame having means for securing a book therein and oppositely extending page-supporting wings hinged on the respective side members of said center frame so mounted that when disposed in open position the ends of the material from which said wings are formed register and engage with shoulders on said plates and function as stops, preventing said page-supporting wings from swinging beyond their open position; a handle positioned intermediate the edges of said respective page-supporting wings adapted for use in grasping and holding the device while reading and otherwise.
- 20 5. A book holder formed from wire including a center frame with parallel side members, page-supporting wings hinged thereon; said wings having respectively intermediate their edges a handle adapted for use in grasping and holding the device.
- 25 6. A book holder formed from wire including a center frame with parallel side members, page-supporting wings hinged thereon; plates spanning said side members, gripping fingers on same which pass under, over and about said side members so as to firmly clinch the same, said plates and fingers also adapted to form an anchorage with in which the hinges of the page-supporting wings operate.
- 30 7. In testimony whereof we affix our signatures.

CLARENCE R. SNOW.
DANIEL J. FLOOD.
